UNITED STATES PATENT OFFICE

2,136,722

IRONING MACHINE

John J. McCabe, Cleveland, Ohio, assignor to The
Apex Electrical Manufacturing Company,
Cleveland, Ohio, a corporation of Ohio

Application March 21, 1934, Serial No. 716,632

29 Claims.

(Cl. 38—59)

This invention relates to ironing machines and it constitutes in part a continuation of my copending applications Serial No. 664,766, which issued on February 23, 1937, as Patent No. 5 2,071,888, and Serial No. 664,767, which issued on January 12, 1937, as Patent No. 2,067,719, both of which applications were filed on April 6, 1933.

The present invention has for one of its objects the provision of an improved ironer shoe support and adjustable tensioning means for effecting resilient pressing engagement between an ironer roll and an ironer shoe.

Another object of the invention has to do with an improved form of manually operable safety release for the ironer shoe which, upon the application of a relatively slight force, may be operated either to instantly release the shoe from contact with the roll or to bring the shoe into pressing engagement with the roll.

Another object of the invention relates to certain improvements for rotatably supporting an ironer roll and for automatically and selectively connecting and disconnecting it with respect to the ironer motor when the shoe and roll are brought into and separated from pressing engagement respectively.

Another object of the invention involves the provision of a friction clutch with improved and generally simplified means for preventing frictional drag between the cooperating driving and driven clutch parts upon the disengagement thereof.

Another object of this invention is concerned with the provision of an improved flexible shoe support adapted to permit resiliently restrained tilting movement of the shoe with respect to its length.

A further object of the invention relates to the provision of an ironing machine of sturdy and inexpensive construction having a generally simplified power driven mechanism for effecting the operation of the machine.

With these and other objects in view, the invention consists in the novel construction, arrangement and combination of parts, hereinafter illustrated and described in some of its embodiments in the accompanying drawings, and particularly pointed out in the appended claims.

In the drawings, Figure 1 is a side elevational view partly in section illustrating some of the details of one embodiment of this invention;

Figure 2 is an enlarged detail view of the clutch and associated gearing of the ironing machine illustrated in Figure 1;

Figure 3 is a sectional view taken on line 3—3, Figure 1;

Figure 4 is an enlarged detail view of one of the roll driving gears;

Figure 21 is an enlarged sectional view taken on line 21—21, Figure 14 illustrating certain details 5 of the connection between the shoe of the ironer and its supporting arm; and

Figure 22 is a side elevational view of a modified form of mechanism which can be used in place of the toggle joint shown in Figures 15 and 17.

10 The ironing machine shown in Figures 1 to 12 is of the type which is adapted for domestic use. The machine is provided with a stand or supporting structure including a base member 1, carried on supporting legs 2 which may be provided with 15 casters (not shown) to facilitate the movement of the machine about from place to place. A combined motor cap and ironer supporting member 3 is fixedly secured at one side to the base member 1 and at its opposite side it is secured to 20 the stator stack 4 of an electric motor which is provided for driving the ironer.

25 A switch having an operating member 5 at the front of the ironer is provided for controlling the operation of the motor. Fixedly secured to the upper side of the stator 4 of the motor, there is secured an integrally formed combined cast metal motor cap and gear case 6. The part 6 houses most of the operating mechanism of the machine and it supports an ironing roll 7 having suitable 30 padding 8 and a shoe 10 having an electric heating element 11 and rear cover 12. The current supply of the heating element of the shoe is controlled by means of a switch (not shown) which is located alongside of and behind the motor controlling switch 5 shown in Figure 1.

35 The casting 6 has a centrally bored boss 13 which provides a bearing for the shaft 14 of the electric motor, such shaft being provided at its outer end with a worm 15, meshing with a worm 40 gear 16, which is mounted for rotation in the casting 6. The worm gear 16 is threadably secured to a cup-shaped clutch member 17 having an axially extending part 18 which is keyed at 19 to a shaft 20. The opposite ends of this shaft are 45 mounted in ball bearings 21 and 22.

50 A pinion 23 is threadably secured to the projecting part 18 of the cup-shaped member 17. The worm 15 thus serves to drive the worm gear 16, the clutch member 17 and the pinion 23 at all 55 times during the operation of the motor. The annular rim 24 of the cup-shaped member 17 serves as one of the driving elements of a roller type clutch, the driven element of which is formed by a member 25 having cam faces 26 and 27 and 55 coacting rollers 28 and 30.

60 The roller 28 coacts with the cam face 26 and the rim part 24 to provide driving connection between the clutch parts for movement in one direction and the roller 30 coacts with the cam face 27 and the annular rim part 24 to provide driving connection between the clutch parts for movement in an opposite direction. Suitable springs 31 and 32 having associated plungers 33 and 34 are provided to urge the rollers 28 and 30 65 into driving engagement with the driving and the driven clutch parts.

65 The engagement between the driving clutch member 24 and the driven clutch member 25 is under control of a member 35 which is rotatably and loosely carried on the shaft 20. The clutch control member 35 has a laterally projecting finger 36 provided for engaging and shifting the roller 30. An oppositely projecting part 37 is provided at one end of the member 35 for contact engagement with the stops of a member which is

70 to be described in detail presently. The opposite end 38 of the member 35 provides an abutment for the spring 31.

75 During the operation of the motor the driving clutch member 24 rotates continuously. The actuation of the clutch control member 35 and the engagement and disengagement between the driving and driven clutch members 24 and 25 respectively is effected by means of a shiftable plate-like member 39 having offset stops 40 and 41 10 which can be moved into and out of the path described by the offset part 37 during its rotation about the axis of the shaft 20.

15 The stops 40 and 41 engage the part 37 at points spaced substantially one hundred and eighty degrees apart with respect to the circular path traveled by the member 37 about the axis of the shaft 20. Normally the member 39 is maintained so that its stops 40 and 41 are in the path of travel of the offset part 37 of the clutch controlling member 35 to hold the same in a position corresponding to its clutch disengaging position.

20 The following action of the parts, shown best in Figure 2, takes place during the disengagement of the clutch. The part 37 upon initial contact 25 of one or the other of the stops 40 or 41 causes the member 35 to pivot a slight amount about the roller 30 compressing the spring 31. This movement is made possible by reason of the loose fit of the member 35 about the shaft 20. As viewed in 30 Figure 2 when the member 35 contacts with the upper side of the shaft 20 further compression of the spring 31 is prevented and the finger 36 then moves the roller 30 out of connecting engagement with the cam face 27 and the inner surface of the 35 rim 24, thereby disengaging the driving connection between the driving and the driven members of the clutch.

40 Upon the stoppage of the driven parts of the clutch the spring 31 operates to further move the 45 roller an additional amount from its initial released position until the clutch control part 35 assumes the position relative to the shaft 20 as illustrated in Figure 2 of the drawings, whereupon no further movement of the clutch parts takes 50 place until the clutch stop in contact with the offset part 37 is withdrawn from obstructing position. A cam member 42 having a slot through which the finger 37 projects is carried over one end of the clutch and serves as a cover therefor. 55

55 The purpose of arranging and operating the aforesaid clutch parts in the manner described is to prevent frictional drag between the driving and the driven clutch parts when the clutch is disengaged. In the present construction the 60 spring 31 has the added function of moving the roller 30 to a completely disengaged position with respect to the cooperating driving and driven clutch parts, thereby eliminating frictional drag in the clutch and also preventing overheating of 65 the clutch by reason of such frictional drag.

70 The highly important results just described are made possible by the simple expedient of providing an enlarged opening in the clutch controlling member 35 for the reception of the shaft 20 65 and by utilizing the clutch roller spring 31 in the manner described, the complete arrangement being one of utmost simplicity and relatively inexpensive construction. The reversely acting cam face 26 and the roller 28 are provided to prevent overrunning of the driven clutch parts 75 with respect to the driving clutch part when the shoe and roll are separated from yielding pressing contact with each other about which more will be said later.

- Separate hand and foot operated means are provided for optionally controlling the clutch. The hand operated clutch control means comprises an external button 43 located at the front 5 side of the machine where it may be easily reached by the operator. This button is mounted on the end of a plunger rod 44 which is secured at its other end in any suitable manner, such as by means of the pin 45, to the slideable clutch control plate 39. In a similar manner a pin 46 is used to secure a plunger rod 47 to the opposite end of the plate 39. A spring 48 is carried at this point to normally maintain the plate 39 in the position shown in Figure 3 of the drawing 10 which position corresponds to the position of disengagement for the clutch. Oil seals 49-49 engage with the plunger rods 44 and 47 to prevent the escape of lubricant from the gear case casting 6. 15
- 20 The plunger 47 is slidably carried in a threaded coupling member 50 which serves as a support means for one end of a flexible conduit 51 within which there is provided a flexible control wire 52 which is secured at one end by means of a 25 threaded member 53 to a similarly threaded end part of the rod 47. The other end of the flexible wire 52 is adjustably secured by means of a set screw 53a to a bell crank 54, pivoted at 55 to a floor engaging supporting fixture 56 which is provided with a foot operated button 57 fixedly secured to a plunger 58, provided for contacting with one arm of the bell crank 54. The other arm of the bell crank is provided with an offset part 60 which is engaged by one end of a compression 30 spring 61, the other end of which abuts against the underside of the supporting fixture 56. 35
- From the foregoing it is apparent that the driving engagement between the cooperating clutch members 24 and 25 may be readily effected by 40 pressing either the hand button 43 or the foot button 57 whichever happens to be most convenient for the operator or for the class of work being ironed. In the actuation of the aforesaid buttons they are pressed in only momentarily. 45 This operation permits the driving and driven clutch parts 24 and 25 to move into engagement with respect to each other for upon release of the finger 37 the spring 32 moves the roller 30 into frictional engagement with the cam face 27 and the rim 24. 50
- The driven clutch part is then rotated about one-half turn until the finger 37 engages one or the other of the stops or offset parts 40 or 41 of the control plate 39 whereupon the disengagement of the clutch parts is effected in the manner previously described and the driven clutch part 25 remains stationary until the aforesaid clutch controls are again operated. The movement of the driven clutch part serves to drive the cam 42 which is fixedly secured to the driven clutch part 25 by any suitable means such as the rivets 62. 55
- The cam 42 is in contact engagement with a roller 63 rotatably carried on one end of a lever 64 which is rigidly secured by means of a pin 66 to a rotatably mounted tube 67 and a spring torsion rod 68. The roller 63 of the crank 64 is maintained in contact with the cam 42 by means of a spring 65 which abuts at one end in a suitable pocket formed in the gear case casing 6 and which at the other end is received in a suitable recess provided by the crank arm 64. 70
- The rod 68 is provided with screw threads at its opposite ends and one of these threaded ends of the rod is received in a threaded cylindrical mem- 75
- ber 69 located inside the fixed end of the tube 67. The member 69 is also fixed with respect to the lever 64 by the pin 66. The outer end of the torsion rod 68 is threaded into a crank member 70. This member has an arm 71 which is provided with a threaded hole for reception of an adjusting screw 72. The parts attached to the threaded ends of the rod 68 are locked in their adjusted positions by means of a pair of lock nuts 73-73. Preferably the ends of the rod 68 are threaded so that the twisting the rod is subjected to will tend to further tighten the nuts 73 and if desired other means may be used for insuring the locked engagement between the rod and the members attached to its ends. 15
- The gear case casting 6 is provided with a laterally extending hollow boss 74 in which is rigidly fitted one end of a supporting tube 75. In the opposite ends of this tube are fitted bushings 76 and 77 which provide bearings for the 20 tube 67. A pair of crank members 78 and 79 are rotatably mounted on the outer end of the tube 67 and they are held in position thereon by any suitable means such as a bolt 80 threaded into the outer end of the tube 67. A T-shaped slot 25 81 is formed in this end of the tube 67 to provide means for locating the crank member 70 in position in the tube and also to permit the arm 71 of this crank member to have a certain limited amount of rotational movement with respect to 30 the axis of the tube 67. The crank member 78 is also cut away at 82 for the accommodation of the arm 71 of the crank 70. 35
- The torsion rod 68 acts as a spring for providing resilient pressing engagement between the ironer shoe and the ironer roll. The adjusting screw 72 is provided to pre-load the torsion rod 68 to provide a predetermined pressure between the roll and shoe when they are in engagement with each other. This pre-loading of the rod is 40 made possible by reason of the fact that the ends of the rod 68 and the tube 67 are rigidly secured to each other at one end and at their other ends the adjusting screw 72 of the arm 71 of the crank member 70 which is fixed to the end of the rod 45 68 engages with the arm 84 of the crank member 78 which is journaled on the end of the tube 67. The crank 78 has a set screw 83 which normally contacts with one end of the crosswise part of the T-shaped slot 81 so that the tube 67 and 50 55 the crank arm 84 of the crank 78 can oppose the twisting moment of the torsion spring 68. 60
- The crank arm 84 is connected by means of an end-threaded stud shaft 85 to one end of a toggle joint formed by a pair of toggle links 86 and 87 which are pivotally joined to each other by means of an end-threaded stud shaft 88. At its outer end the link 87 is pivotally secured by means of an end-threaded stud shaft 89 to the arm 90 of the crank member 79 which is journaled 65 on the outermost end of the tube 67. Another arm 93 of the crank member 79 pivotally carries the ironer shoe 10 at its outermost end. 70
- The shoe 10 is flexibly secured at a point intermediate its length to the arm 93 by means of a pair of rearwardly projecting relatively resilient yielding ears 94-94 fixed to the shoe and which have non-circular openings 95 for receiving correspondingly formed notched ends of a pin 96, the intermediate part of which is formed with a 75 channeled or grooved part 97, the ends of which are arranged to engage with a screw 98 fixedly carried by the arm 93 of the crank 79. The end of the screw 98 cooperates with the ends of the channeled or grooved part of the pin 96 to provide

stops for limiting the movement of the shoe 10 about the axis of the pin 96. The shoe contacting ends 99 of the ears 94 which may be secured to the shoe by means of the rear cover thereof are offset a slight amount to permit the shoe ends to tilt in a slightly restrained manner a small amount with respect to the roll as is necessary for the accommodation of articles being ironed which vary in thickness along the line of contact between the ironer roll and shoe.

The limiting positions of the shoe are shown in full and dotted lines respectively in Figure 6 of the drawings. The full line position corresponds to the operative ironing position of the shoe and the dotted line position corresponds to the position the shoe may be shifted to for the purpose of cleaning or polishing the ironing surface thereof. The T-shaped slot 81 of the tube 67 is positioned and located so that the stop screw 83 moves only a slight distance from the end of the slot when the shoe is moved into pressing engagement with the roll, thus permitting maximum separation between the roll and shoe for the various tension adjustments of the rod 68.

The elements described thus far, relate primarily to the members provided for the actuation of the shoe as well as the means provided for insuring yielding pressing contact between the roll and the shoe when they are in engagement with each other. Normally during the operation of the driving motor of the ironer the roll 7 is stationary. When the shoe moves into contact with the roll, the roll is automatically connected in driven relation to the motor, and conversely when the shoe is moved away from the roll such driving connection between the motor and the roll is automatically disconnected.

The driving of the roll is effected through the constantly driven gear 23 which serves to drive a gear 102, in meshing engagement therewith. The gear 102 is fixed to one end of a shaft 103 and at its other end this shaft carries a gear 104 which is free to rotate a slight amount on the shaft under restraint of a coiled spring 105. The gear 104 has an enlarged keyway or slot 106 for loosely receiving a key 107 fixedly carried by the shaft 103 and by means of which the gear 104 is driven.

The teeth of the gear 104 normally rotate clear of the teeth of an internal gear 108, fixedly secured in one end of the roll 7 by any suitable means such as the screws 110. One end of the roller 7 is provided with a radially movable bearing 111 and at its other end the roller is rotatably supported by means of a bearing 112 which is arranged to permit slight radial movements of the opposite end of the roller. The roller 7 is held in position on a supporting shaft or tube 113 by means of a suitable bolt 114 and washer 115 carried on the end of the tube.

The movable bearing member 111 has an elliptical slot 116 traversed by the roll supporting shaft or tube 113. The slot 116 is provided to permit certain limited radial movements of the bearing 111 and the end of the roll relatively to the tube 113. The gear case casting 6 is provided at one side with an extending part 117 having drilled radial openings at one edge for reception of a pair of springs 118-119. These springs press suitable plungers 119-119 against the bearing member 111 urging such bearing member and the end of the roll supported thereon in a direction radially of the tube 113 to maintain the gears 104 and 108 out of mesh. The web 75 of the bearing member 111 has a slot for receiv-

ing a bolt 120 carried by the gear case part 117. The bolt is provided to prevent rotation of the bearing while at the same time permitting the described radial movements of the bearing.

When the shoe is moved into engagement with the roll the end of the roll carrying the gear 108 moves a slight amount with the shoe until the bearing 111 is brought into contact with the edge 121 of the gear case part 117. As this movement is effected the gears 104 and 108 are brought into meshing engagement with each other and the roll is thus connected in driving relation with respect to the ironer motor and it is rotated continuously during the operation of the ironer motor until the shoe is withdrawn from the contact with the roll. In the event that the teeth of the gears 104 and 108 are not in proper alignment at the time of their initial contact the permissible spring restrained movement of the gear 104 with respect to its shaft will allow sufficient relative movement between the gears 104 and 108 to insure proper meshing engagement between these gears. The ends of the teeth of the gear 104 are rounded off as shown in Figure 4 to facilitate their meshing engagement with each other.

It is sometimes desirable to operate the machine without rotating the roll as for example when it is intended to use the machine as a press rather than as an ironing machine. Means are provided for preventing the roll driving gears 104 and 108 from being moved into engagement with each other. These means comprise a rotatable pin 122 which is carried in the offset part 117 of the gear case casting 6. This pin is held in position by means of a ball 123 which is urged by a spring 124 into an annular slot 125 formed in the pin 122. One end of this pin is notched at 126 and it also has a hole drilled in its side for receiving an operating rod 127 having a handle 128 by means of which the pin is rotated about its axis.

When the pin is rotated from the position shown in Figure 3 the side of the pin is presented to the bearing member 111 and as the pin is rigid in so far as radial movement with respect to the roll axis is concerned, when the shoe 45 is brought into engagement with the roll the meshing engagement between the gears 104 and 108 is thus prevented. The operating handle 128 is positioned above the roll at one end thereof where it may be easily manipulated by the user 50 of the machine.

Other means are provided for utilizing the machine as a press. These means comprise an operating lever 130 which is pivoted at a point intermediate its length to the base 1 of the machine by means of a pin 131. At its other end the lever 130 is pivotally connected by a pin 132 to a link 133 which in turn is pivotally connected by the stud shaft 88 to the point where the toggle links 86 and 87 are joined to each other. These links normally are out of line a slight amount and thus have a tendency to press against an adjustable screw 134 which is threadably received in the crank member 78. Under ordinary operating conditions the toggle links 86 and 87 will maintain the substantially aligned position shown in Figure 9 of the drawings.

When the lever 130 is raised from the position shown in Figure 1 of the drawings and when the shoe and the roll are in pressing engagement with each other, the connection provided by the toggle links 86 and 87 is broken and the shoe can be manually moved away from the roll. In a similar manner when the lever 130 is manually

moved downwardly from the position last described, the toggle links 86 and 87 are brought into alignment and the shoe is thus forced into pressing contact with the roll.

5 The stated operations can be performed without the use of the driving motor of the ironer, and the elements just described also serve as a safety release for moving the shoe away from the roll as might be necessary in the event of stoppage of the motor or in case one of the operator's hands is drawn between the roll and the shoe. The breaking of the toggle joint requires the exertion of but a very slight pressure on the handle 130 and due to the great leverage provided by the handle 130 and the toggle links the reverse movement of the shoe into pressing engagement with the roll is accomplished with equal ease.

10 In the modified form of construction shown in Figures 13 to 22 of the drawings, the ironing machine illustrated follows in general the form of machine shown in my Patent No. 2,067,719, and it comprises a table-like structure 140 for the support of the ironer which has a rotatable roll 141 and a heated shoe 142. Suitable gearing and driving mechanism are housed within a gear case 143 located at one end of the roll and shoe. The mechanism and gearing in the gear case 143 is arranged to rotate the roll and also to move the roll toward and away from the shoe as indicated in dotted lines in Figure 15. The shoe is flexibly mounted to provide for resilient pressing contact between the roll and the shoe when the roll is moved into contact with the shoe.

15 In so far as the improvements of the machine shown in Figure 13 are concerned mainly with the shoe and its supporting means, further reference will not be made to the operating mechanism of the roll, other than to state that its movements are under control of a push button 144 which is conveniently mounted at the top of the gear case 143.

20 The shoe 142 at its rearward side is provided with a pair of ears 145—145 of similar construction to the shoe supporting ears mentioned in connection with the description of the machine shown in Figures 1 to 12 and such ears are provided with non-circular holes 146—146 for receiving the notched ends of a shoe supporting pin 147 which is rigidly secured to the ears by means of a pair of bolts 148.

25 The pin 147 is provided with a circumferential channel 150 intermediate its length which extends part way around the pin axis. The grooved part of the pin is received in a suitable bearing provided at the upper end of a shoe supporting arm 151 which is drilled and threaded for the reception of a screw 152. The end of this screw projects into the channelled slot 150 of the pin 147 and the screw thus serves to limit the movement of the shoe about the axis of its pin 147 so that the shoe may be rotated to present its surface in a position corresponding to the position shown in dotted lines for the form of the invention shown in Figure 6 of the drawings, whereupon the ironing surface of the shoe may be cleaned or polished.

30 The shoe supporting arm 151 is provided with a spring 153 at a point intermediate its ends. The spring 153 is held in position on the shoe supporting arm by means of a screw 154 and at its outer exposed end the spring is provided with a cap 155. The spring 153 engages the lower edge of the shoe and serves to move the shoe a slight amount about the axis of the pin 147 when the

35 roll and shoe are not in pressing contact, the purpose being to insure that the trailing edge of the shoe is the first to engage the roll when they are moved into pressing contact with each other. This arrangement and mode of operation helps to prevent wrinkling of the articles being ironed as sometimes occurs when the front edge of the shoe engages the roll and an article to be ironed, at or before the time the rest of the shoe engages the roll.

40 The shoe supporting arm 151 is secured to a torsion rod 156 by means of a pin 157. The torsion rod 156 is journaled in suitable bearings 158 and 160, the former of which is carried in a shoe supporting tube 161 and the latter of which is rigid with and surrounded by a boss 162 of the gear case 143. At this end of the rod 156 a crank arm 163 is secured by means of a pin 164. The other end of the crank arm is pivotally connected by means of a stud shaft 165 to one end of a toggle link 166, the other end of which is pivotally connected by means of a pin 167 to the end of a lever 168 which forms the cooperating link of the toggle joint.

45 Intermediate its length the lever 168 is pivoted at 170 to a supporting bracket 171 carried by the supporting structure 140 of the ironer. An operating handle 172 is provided for the manipulation of the lever 168. When the operating handle 172 is depressed the toggle is broken and the shoe is moved rearwardly away from the roll. When the handle 172 is raised to the position last described, the toggle is brought into its aligned position and the shoe is moved to the position shown in Figure 15 of the drawings.

50 This arrangement provides a safety release for moving the shoe away from the roll and it also serves to utilize the machine as a pressing device without necessitating the need of operating the motor as the leverage of the operating handle is so great that very little force is necessary to bring the shoe and roll into pressing engagement. A stop 173 carried by the member 171, engages the lever 168 when the toggle is moved to its locked or aligned position. In practice it is preferred, when the lever 168 is in engagement with the stop 173, to have the toggle normally out of alignment a slight amount so that there is a tendency to maintain the aforesaid parts in this position.

55 The torsion rod 156 is ordinarily pre-loaded a slight amount which loading may be varied by means of an eccentric part 174 formed on the stud shaft 165 which eccentric part is journaled in the lower end of the crank 163. An adjusting member 175 having a rectangular hole for reception of a similarly formed part of the stud shaft 165 is provided for adjusting the eccentric 174. This member has an operating handle 176 which is held in various desired positions of adjustment by means of a series of notches 179 formed in the rearmost end of the toggle member 166. The adjusting member 175 is urged against this end of the toggle member by means of a spring 177 which is held on the stud shaft 165 by means of a pin 178 and by the reason of this arrangement the edge of the handle 176 may be maintained in any one of the notches 179. Both the spring means or torsion rod 156 and the manually operable cam or eccentric part 174 are interposed in the shoe supporting means and they are located intermediate the shoe and its operating member or handle 172. The eccentric part 174, the operating handle 176 and the notches 179 constitute a cam with multiple stages or a mul-

multiple stage adjustment by means of which the ironing pressure may be adjusted to a plurality of different pressures.

Due to the pre-loading of the rod 156 there is a tendency for the shoe to follow the roll when the roll is moved away from the shoe. This movement is limited in extent by means of an adjustable bolt 180 fixed in the base 140 which engages with a part 181 carried by and rigid 10 with the shoe supporting arm 151. The adjustment of the aforesaid parts normally is such that when the shoe and roll are in pressing contact the part 181 is maintained out of contact with the bolt 180 a very slight amount. A bolt 15 182 which is threaded into the bearing 158 is used to secure the hollow casting 183 to the base 140 and to the end of the tube 161. This casting is formed with smoothly blended surfaces and serves to conceal the end of the shoe supporting arm 151 and also to add considerably to the finished appearance of the ironer. The casting 20 183 also assists in supporting the shoe of the machine, in stiffening the base 140 and in strengthening and increasing the rigidity of the 25 entire supporting structure of the ironing elements of the machine.

In Figure 22 a modified form of shoe release mechanism is shown which can be used in place of the arrangement shown in Figure 15 and in 30 which the shoe operating crank member 163 would be replaced by a crank member 191 having a roller 192 at its lower end. This roller is engaged by a cam 190 fixed to one end of a shaft 185 which is journaled in a bearing 186 carried 35 by the base 140 of the ironer. The depending skirt at the front of the base member 140, is received between a collar 187 and a crank 193, fixed to the other end of the shaft 185.

The crank 193 has an operating handle 194 by 40 means of which the cam 190 may be rotated to manually move the shoe toward and away from the roll. The profile of the cam 190 preferably is arranged so that the greatest leverage of the shoe shifting mechanism is available just before 45 the shoe reaches its operative position and for other positions of the shoe a given movement of the handle 194 will effect a relatively large movement of the shoe. The toggle joint mechanism shown in Figures 15 and 17 will also operate in much the same manner it being a characteristic 50 of such joints that the mechanical advantage of the system rapidly increases as the links of the joint are brought into alignment.

From the foregoing it is apparent that the 55 ironing machine described herein has many advantages and improvements, some of which include the use of the machine as a pressing device without requiring the operation of the driving motor, the use of a torsion rod to provide for 60 the pressing contact between the roll and shoe, the elimination of the customary clutches and their operating means ordinarily used in starting and stopping the operation of the roll, the provision of an easily operated safety shoe release 65 and manually operated pressing device, the provision of an improved and simplified means for adjusting the pressure between the roll and the shoe, such means including provisions to maintain a constant clearance between the roll and 70 the shoe when they are separated from each other, the provision of an ironing machine of pleasing and attractive appearance, and the provision of a generally simplified and inexpensive mechanism for accomplishing the desired results.

75 Furthermore it is to be understood that the

particular forms of apparatus shown and described, and the particular procedure set forth are presented for purposes of explanation and that various modifications of said apparatus and procedure can be made without departure from this invention as described in the appended claims.

Having thus described my invention what I claim is:

1. An ironing machine comprising, a supporting structure, a padded roll rotatably mounted thereon with one end only of said roll arranged for radial movement, a cooperating heated ironing member also carried by said supporting structure, power means for rotating said roll including an internal gear fixed inside the roll at the radially movable end thereof and a driving pinion normally out of mesh therewith, and means for effecting relative movement between said roll and member for bringing them into pressing contact 20 with each other and for radially moving the end of the roll to bring said gear and pinion into meshing engagement with each other.

2. In an ironing machine, a relatively rigid supporting structure, a roll rotatably mounted thereon, a cooperating ironing member also carried by said supporting structure, and means for effecting relative movement between said roll and member towards and away from each other for bringing them into yielding pressing engagement 30 and for separating them from each other selectively, such means comprising a spring torsion rod and means for preloading said spring torsion rod a substantial amount when said roll and member are separated for increasing the pressure between 35 said roll and ironing member when they are brought into pressing engagement with each other.

3. In an ironing machine, a relatively rigid supporting structure, a roll rotatably mounted thereon, a cooperating ironing member also carried by said supporting structure, and power means for effecting relative movement between said roll and member toward and away from each other for bringing them into pressing engagement and for separating them from each other selectively, such means comprising a source of power and a spring torsion rod providing a yielding operative connection between said member and said source of power and means for preloading said spring torsion rod a substantial amount when said roll and member are separated for increasing the pressure between said roll and ironing member when they are brought into pressing engagement with each other.

4. An ironing machine comprising, cooperating ironing members including a padded rotatable roll and a heated shoe, power means for rotating said roll and for shifting one of said ironing members alternatively into and out of pressing engagement with the other, and independent manually operable means for shifting the other of said ironing members into and out of pressing engagement with the power shifted ironing member, said manually operable means including an 65 operating member located adjacent to the front of the machine where it is readily accessible for use by the machine operator.

5. An ironing machine comprising, cooperating ironing members including a padded rotatable 70 roll and a heated shoe, power means for rotating said roll and for shifting said roll alternatively into and out of pressing engagement with said shoe, and independent manually operable means for shifting said shoe into and out of pressing 75

engagement with said roll, said manually operable means including an operating member located adjacent to the front of the machine where it is readily accessible for use by the machine operator.

5 6. In an ironing machine, a relatively rigid supporting structure, a roll rotatably mounted thereon, a cooperating ironing member also carried by said supporting structure for movement between operative and inoperative positions, and
10 means for moving said ironing member into or out of pressing engagement with said roll, such means comprising a spring torsion rod and means connecting one end of said rod to said ironing member, said rod being secured at its other end
15 to devices carried by said supporting structure whereby the rod provides for yielding pressing contact between said roll and ironing member, and adjustable means for increasing the pressure exerted by said rod between said roll and ironing member when they are brought into engagement with each other without however decreasing the amount of separation between said roll and ironing member when the ironing member is in its inoperative position.

20 7. In an ironing machine, a relatively rigid supporting structure, a roll rotatably mounted thereon, a cooperating ironing member also carried by said supporting structure for movement between substantially fixed operative and inoperative positions, and means for moving said ironing member into or out of pressing engagement with said roll, such means comprising a spring torsion rod and means connecting one end of said rod to said ironing member, said rod being secured at its other end to devices carried by said supporting structure whereby the rod provides for yielding pressing contact between said roll and ironing member, means for adjusting the pressure exerted by said rod between said roll and ironing member when they are brought into engagement with each other without however changing the amount of separation between said roll and ironing member when the ironing member is in its inoperative position, and a manually operable safety device associated with said rod securing devices for releasing the securement of said rod with respect to said supporting structure.

25 8. In an ironing machine, a shoe, and a yielding supporting structure for said shoe comprising, a rigid shoe supporting arm, an offset resilient member fixed at one end with respect to said shoe at a point intermediate the length thereof, said resilient member being offset in a direction parallel to the axis of the shoe whereby tilting of such shoe axis may take place in ironing work of irregular thickness, and means for pivotally securing the other end of said resilient member to said shoe supporting arm.

30 9. An ironing machine comprising, a supporting structure, a padded roll rotatably mounted thereon, a cooperating heated ironing member also carried by said supporting structure, means for effecting relative movement between said roll and member for bringing them into pressing contact with each other, and power means for rotating said roll including power transmission means having a portion fixed to rotate with said power means and another portion fixed to rotate with said roll and constituting a disconnectible driving connection between the portions of said power transmission means which is engageable in response to the contact pressure between said roll and member.

35 10. An ironing machine comprising, a support-

ing structure, a padded roll rotatably mounted thereon, a cooperating heated ironing member also carried by said supporting structure, means for moving said heated ironing member into and out of pressing contact with said roll, and power means for rotating said roll including power transmission means having a portion fixed to rotate with said power means and another portion fixed to rotate with said roll and constituting a disengageable driving connection between the portions of said power transmission means in which driving engagement thereof is effected in response to the contact pressure between said roll and member when they are brought into contact with each other.

40 11. An ironing machine comprising, a supporting structure, a padded roll rotatably mounted thereon, a cooperating heated ironing member also carried by said supporting structure, means for effecting relative movement between said roll and member for bringing them into pressing contact with each other, and power means for rotating said roll including power transmission means having a portion fixed to rotate with said power means and another portion fixed to rotate with said roll and constituting a disengageable connection between the portions of said power transmission means in which driving engagement is effected and maintained in response to the contact pressure between said roll and member when they are in contact with each other.

45 12. An ironing machine comprising, a supporting structure, a padded roll rotatably mounted thereon, a cooperating heated ironing member also carried by said supporting structure, a motor, means driven by said motor for effecting relative movement between said roll and member for bringing them into pressing contact with each other, means driven by said motor for rotating said roll including power transmission means having a portion fixed to rotate with said motor and a cooperating portion fixed to rotate with said roll and constituting a disconnectible driving connection between the portions of said power transmission means which is engageable in response to the contact pressure between said roll and member, and operator-operated means for preventing at the will of the operator, rotation of the roll when said roll and member are brought into contact with each other.

50 13. An ironing machine comprising, a supporting structure, a padded roll rotatably mounted thereon, a cooperating heated ironing member also carried by said supporting structure, means for effecting relative movement between said roll and member for bringing them into pressing contact with each other and for moving said roll laterally of said supporting structure, and power means for rotating said roll including power transmission means having a portion fixed to rotate with said power means and a cooperating portion fixed to rotate with said roll and constituting a disconnectible driving connection between the portions of said power transmission means which is engageable in response to the contact pressure between said roll and member.

55 14. An ironing machine comprising, a supporting structure, a padded roll rotatably and movably mounted thereon, a cooperating heated ironing member also carried by said supporting structure, means for effecting relative movement between said roll and member for bringing them into pressing contact with each other and for moving one end of said roll radially of its axis of rotation, and power means for rotating said

- roll including power transmission means having a portion fixed to rotate with said power means and a cooperating portion fixed to rotate with said roll and constituting a disconnectible driving connection between the portions of said power transmission means which is engageable in response to the contact pressure between said roll with said member.
15. An ironing machine comprising, a supporting structure, a padded roll rotatably mounted thereon, a cooperating heated ironing member also carried by said supporting structure, means for effecting relative movement between said roll and member for bringing them into pressing contact with each other, and power means for rotating said roll including normally disengaged driving and driven gears mounted for relative bodily movement and movable into driving engagement with each other in response to the contact pressure between said roll and member.
16. An ironing machine comprising, a supporting structure, a padded roll rotatably mounted thereon, a cooperating heated ironing member also carried by said supporting structure, power means for rotating said roll including a driven gear fixedly carried by the roll and a cooperating driving gear fixed to rotate with said power means, said gears being mounted for relative movement into and out of meshing engagement with respect to each other in response to the application and release of contact pressure between said roll and member, and means for effecting relative movement between said roll and member for bringing them into pressing contact with each other and for connecting said driving and driven gears as aforesaid.
17. An ironing machine comprising, a supporting structure, a padded roll rotatably mounted thereon, a cooperating heated ironing member also carried by said supporting structure, power means for rotating said roll including power transmission means comprising a driving part operatively connected to said power means and a driven part operatively connected to said roll, said parts being movable into engagement with each other in response to contact pressure between said member and roll, and manually operable means for effecting relative movement between said roll and member to bring them into pressing contact with each other and for effecting driving engagement of the driving and driven parts of said power transmission means.
18. An ironing machine comprising, a supporting structure, a padded roll rotatably mounted thereon, a cooperating heated ironing member also carried by said supporting structure, power means for rotating said roll including power transmission means comprising a driving part operatively connected to said power means and a driven part operatively connected to said roll, said parts being movable into engagement with each other in response to contact pressure between said member and roll, and manually operated means and power operated means either of which is independently usable for effecting relative movement between said roll and member to bring them into pressing contact with each other and for effecting driving engagement of the driving and driven parts of said power transmission means.
19. In an ironing machine, cooperating ironing members, a flexible supporting structure for one of said ironing members comprising a pivot pin and a pair of resilient elements, each being fixedly secured at one end to such ironing member and fixedly secured at their other end to said pivot pin and having offset portions intermediate their length, the axis of said pivot pin being arranged longitudinally of said ironing member so as to permit movement thereof about such axis, said elements being adapted because of their resiliency to permit tilting movements of said last-named ironing member with respect to the other ironing member when the thickness of the goods being ironed is different for different portions of the ironing members between which it is engaged.
20. In an ironing machine, a relatively rigid supporting structure, cooperating ironing elements including a roll rotatably mounted on said supporting structure and an associated ironing member also carried by said supporting structure, and means for effecting relative movement between said ironing elements towards and away from each other for bringing them into yielding pressing contact and for separating them from each other selectively, such means comprising a spring torsion rod, means associated with one end of said torsion rod for operatively connecting the same with respect to one of said ironing elements, an operating mechanism, means associated with the other end of said torsion rod for operatively connecting the same with respect to said operating mechanism and adjusting means including an eccentric interposed between said torsion rod and said operating mechanism for pre-loading said spring torsion rod a substantial amount when said roll and member are separated for increasing the pressure between said roll and ironing member when they are brought into pressing engagement with each other.
21. An ironing machine comprising, a supporting structure, cooperating ironing elements carried by said supporting structure including a heated member and a padded roll, means for mounting said roll for both rotational and lateral bodily movements, shifting means for effecting relative movement between said ironing elements for bringing them into and out of pressing contact with respect to each other, power means for rotating said roll including a source of power and a disconnectible driving connection between the roll and the source of power, said disconnectible driving connection including an element fixed to rotate with said roll and a cooperating element fixed to rotate with said source of power, and means including said shifting means for effecting movement of the aforesaid elements of said disconnectible driving connection into yielding engagement with each other in response to contact pressure between said cooperating ironing elements.
22. An ironing machine comprising, a supporting structure, cooperating ironing elements carried by said supporting structure including a heated member and a padded roll, means for mounting said roll for both rotational and lateral bodily movements, shifting means for effecting relative movement between said ironing elements for bringing them into and out of pressing contact with respect to each other, power means for rotating said roll including a source of power and a disconnectible driving connection between the roll and the source of power, said disconnectible driving connection including a gear fixed to rotate with said roll and a cooperating gear fixed to rotate with said source of power, and means including said shifting means for effecting movement of the aforesaid gears of said disconnectible driving connection into yielding meshing engagement.

ment with each other in response to contact pressure between said cooperating ironing elements.

23. An ironing machine comprising, a supporting structure, cooperating ironing elements carried by said supporting structure including a heated member and a padded roll, means for mounting said roll for both rotational and lateral bodily movements, shifting means for effecting relative movement between said ironing elements for bringing them into and out of pressing contact with respect to each other, power means for rotating said roll including a source of power and a disconnectible driving connection between the roll and the source of power, said disconnectible driving connection including an internal gear fixed inside said roll and rotatable therewith and a cooperating driving pinion located alongside of the internal gear and fixed to rotate with said source of power, and means including said shifting means for effecting movement of the aforesaid gear and pinion of said disconnectible driving connection into meshing engagement with each other in response to contact pressure between said cooperating ironing elements.

24. In an ironing machine of the class described, the combination of an ironing roll, a shoe cooperatively supported therewith, an operating member and inter-connecting mechanism for moving the shoe into contact with the roll including pressure means for resiliently holding the shoe in pressure relation with the roll, and a manually operable cam mechanism intermediate the operating member and shoe for adjusting the pressure of the shoe upon the roll without removing all pressure.

25. In a power driven ironing machine, cooperating pressing members comprising an ironing roll and an ironing shoe, mechanism for revolving the ironing roll and for actuating one of said pressing members into and out of pressure contact with the other pressing member, shoe supporting means, spring means interposed in said shoe supporting means to make the contact between the shoe and roll resilient, and a manually operable cam interposed in the shoe supporting means to adjust the pressure between the roll and shoe.

26. In a power driven ironing machine, the combination of an ironing roll, an ironer shoe, mechanism for revolving the ironing roll and actuating pressure contact between the shoe and the roll, shoe supporting means, spring means interposed in the shoe supporting means to make the contact between the shoe and roll resilient, and a manually operable cam with multiple stages interposed in the shoe supporting means to adjust the pressure between the roll and shoe for variable thicknesses of garments.

27. An ironing machine comprising a stand, a housing structure at one end thereof, a roll support projecting from said housing structure, a padded roll mounted on said support for both rotational movement and bodily movement with respect thereto, an ironing shoe arranged to cooperate with said roll in effecting the ironing and pressing operations when the roll and

shoe are in contact with each other, a power unit, mechanism operatively connected to said power unit to effect relative movement between said shoe and roll and bodily movement of said roll with respect to said support, and means operatively connected to said power unit to rotate said roll comprising a gear within said roll and fixed to rotate therewith, a shaft projecting from said housing structure and a pinion fixed to said shaft inside said roll, said pinion and gear being moved into and out of meshing engagement with each other in response to the actuation of said mechanism in effecting bodily movement of the roll with respect to said support.

28. An ironing machine comprising a stand, a housing structure at one end thereof, a roll support projecting from said housing structure, a padded roll mounted on said support for both rotational movement and bodily movement with respect thereto, an ironing shoe arranged to cooperate with said roll in effecting the ironing and pressing operations when the roll and shoe are in contact with each other, a power unit, mechanism operatively connected to said power unit to effect relative movement between said shoe and roll and bodily movement of said roll with respect to said support, means operatively connected to said power unit to rotate said roll comprising a gear fixed with respect to said roll internally thereof, a shaft projecting from said housing structure and a pinion inside of said roll and fixed to rotate with said shaft, said pinion and gear being moved into and out of meshing engagement with each other in response to the actuation of said mechanism in effecting bodily movement of the roll with respect to said support, and manually controlled means to prevent rotation of said roll upon actuation of said mechanism comprising a member within said roll operatively arranged with respect to said gear and pinion to prevent meshing engagement thereof.

29. An ironing machine comprising, a supporting structure, cooperating ironing elements carried by said supporting structure including a heated member and a padded roll, one of said ironing elements being mounted for relative movement with respect to the other, means including a relatively rigid support extending into said roll for mounting the roll for rotational movement, power means for effecting relative movement of said ironing elements into and out of pressing contact with each other, roll drive means including a pair of gears inside said roll for rotating the roll, one of said gears being adapted to be rotated by said power means and the other gear being adapted to rotate with said roll, and mounting means for said gears operatively associated with said power means for effecting yielding meshing engagement of said gears to rotate said roll when said ironing elements are brought into pressing contact with each other by said power means.

JOHN J. McCABE. 65
